UNITED STATES PATENT OFFICE.

JAMES ARTHUR KIDWELL, OF LAKewood, OHIO.

CHECK-CABINET.

1,340,231.

Specification of Letters Patent.

Patented May 18, 1920.

Application filed August 13, 1917. Serial No. 185,931.

To all whom it may concern:

Be it known that I, JAMES ARTHUR KIDWELL, a citizen of the United States, and resident of Lakewood, in the county of Cuyahoga and State of Ohio, have invented certain new and useful Improvements in Check-Cabinets, of which I hereby declare the following to be a full, clear, and exact description, such as will enable others skilled in the art to which it appertains to make and use the same.

The objects of the invention are to provide improved operating and locking devices for the mechanism of a cabinet employed in registering the trade checks of a check credit system.

The device hereinafter described is an improvement upon the cabinet illustrated and described in my former application for a patent in the United States, filed October 23, 1916, bearing Serial No. 57,432.

In the present device many additional improvements are incorporated including locking means preventing the introduction of the check disks into the several feed slots of the machine.

It includes means for preventing simultaneously the actuating of the counting and registering mechanism which will effectually prevent irresponsible parties from entering records therein.

It includes a registering key operatively connected with said locking device for the check slots, and also operatively connected with a bell which sounds when said key is actuated.

It includes a series of subtracting levers for releasing one check at a time from each slot or check storing receptacle, a bell sounding device operated thereby, and means preventing the operation of the subtracting lever and bell sounding device when the registering key is locked from movement.

It includes a slidable push rod positioned to prevent the movement of the record operating key, and thereby also preventing the introduction of checks into the check slots, the sounding of the bell and the operation of the subtracting lever.

It includes a separate locking slide for the rear extremities of the dumping slides.

The invention is hereinafter more fully described, shown in the accompanying drawings and specifically pointed out in the claims.

In the accompanying drawings Figure 1

is a perspective of the cabinet; Fig. 2 is a vertical transverse section thereof; Fig. 2^a is a detail view of bell operating and slide locking devices; Fig. 3 is a horizontal section of the case showing the check receptacles, the bell, and locking plate for the dumping slides; Fig. 4 is a rear elevation of said locking plate for said dumping slides; Fig. 5 is a vertical longitudinal section of the case showing the check receptacles, registering keys and sliding locking rod therefor.

In these views A represents the casing B, B, B, the check receptacles into which the checks are introduced from above through graduated slots C, C, C, in the casing. D, D, are the subtracting slides which are provided with openings D', D' corresponding in size with the diameters of the respective check receptacles, the openings in the respective receptacles and slides being normally in alinement with each other. Beneath the subtracting slides are shown the dumping slides E, E, E, having similar openings E', E' normally out of alinement with and forward of the openings E on the subtracting slides. A key E², operates each dumping slide, and a key lever E³ pivoted upon a rear shaft E⁴ operates each subtracting slide by means of the intervening bell crank E⁵. A spring E⁶ returns each subtracting slide and a spring E⁶ returns each dumping slide.

F is a key which operates each registering and counting device which may be of any well known character. An arm F' upon the key shaft F² operates the actuating arm F³ of the register when the key is pressed down.

G is a bell crank the clapper of which G' is operatively connected with the movements of the registering key, and also with the movements of the subtracting lever, so that the operation of either will sound the bell. This is accomplished as follows:

When the key is pressed in, a bell crank arm H operates a rod H' which is connected by a rock arm H², which descending strikes a lug H³ pivoted in the bell clapper, and sounds the bell when the record key is released.

A spring H⁴ returns the rock arm H² and bell crank H. A second spring H⁵ returns the bell clapper. When the subtracting levers are depressed and arm H⁶ mounted upon a bar H⁷ underneath said levers is de-

pressed and operates the aforesaid rock arm H^2 by means of the link H^8 and sounds the bell.

5 I is a slide which is movable to cut off ingress to the check receptacles. This slide is automatically operated by the movement of the bell crank H through the agency of the bell crank I' and connecting rod I^2 . A rod J slidably movable in the frame at J' , J' 10 passes in advance of all the registering keys and prevents their movement until the slide is pressed in when the keys will pass through openings J^2 , J^2 therein. This rod is returned by means of the spring J^3 , and the 15 movement is adjusted by means of a screw J^4 .

It will be seen that when the locking rod J is set the machine is practically closed since the checks cannot be put into the receptacles, the registering keys cannot be operated, the subtracting lever is locked by the transverse bar, and the bell can not be sounded.

The dumping slides are locked separately 25 by means of a plate K in the rear of the machine which is raised to cover the ends of the slides and lowered to release them. This is accomplished by means of a vertically movable bolt L for the lock L' . This bolt 30 engages the rock arm L^2 which engages and moves the plate K longitudinally, and screws or pins K' , K' operate in diagonal slots K^2 , K^2 to alternately raise and lower the plate K .

35 Having described the invention what I claim as new and desire to secure by Letters Patent is:—

1. In a check cabinet, a series of graduated

check receptacles, the wall of said cabinet having inlet openings leading thereto, subtracting slides underneath said receptacles and dumping slides beneath said subtracting slide, a bell, and registering devices, means for sounding said bell and for operating said registering devices, and separate means for 45 operating each of said slides, a slide for closing the said inlet openings leading to said check receptacle, means for operating said closing slide, and a device for preventing the movements of said registering devices, a bell sounding device, a closing slide and subtracting slides, and a separate locking device for said dumping slides.

2. In a check cabinet, a series of graduated check receptacles, a slide for closing the entrance to said receptacles, a registering device for each receptacle, an operating key for each registering device, a bell sounding device and a subtracting slide underneath each check receptacle, said operating keys 60 for said registering devices serving to actuate said closing slide, and bell sounding device, a locking means for all said registering operating keys, and means operatively connected with said subtracting keys for sounding said bell, said last named means preventing the operation of said subtracting slides when said registering operating keys are locked from movement substantially as described.

In testimony whereof, I hereunto set my hand this 23 day of July 1917.

JAMES ARTHUR KIDWELL.

In presence of—

W.M. M. MONROE,
S. L. TURNER.
